CLAIM

The ornamental design for a ride-on toy car, as shown and described.

DESCRIPTION

FIG. 1 is a rear, right and top perspective view of a ride-on toy car, showing my new design;
FIG. 2 is a front, left and bottom perspective view thereof;
FIG. 3 is a front view thereof;
FIG. 4 is a rear view thereof;
FIG. 5 is a top plan view thereof;
FIG. 6 is a bottom plan view thereof;
FIG. 7 is a left side view thereof;
FIG. 8 is a right side view thereof;
FIG. 9 is an enlarged view of portion of FIG. 1 thereof;
FIG. 10 is an enlarged view of portion of FIG. 1 thereof;
FIG. 11 is an enlarged view of portion of FIG. 1 thereof;
FIG. 12 is an enlarged view of portion of FIG. 2 thereof; and,
FIG. 13 is an enlarged view of portion of FIG. 2 thereof.
The evenly broken lines disclose unclaimed portions of the ride-on toy car; the dash-dot type broken lines disclose unclaimed boundaries of the isolated views; the broken lines form no part of the claimed design.
